ATTORNEY.

UNITED STATES PATENT OFFICE.

LOUIS WILHELM, OF WORCESTER, MASSACHUSETTS, ASSIGNOR OF ONE-HALF TO FREDERICK A. STEVENS, OF PROVIDENCE, RHODE ISLAND.

LENS-BLANK.

No. 901,575.

Specification of Letters Patent.

Patented Oct. 20, 1908.

Application filed February 18, 1908. Serial No. 416,621.

To all whom it may concern:

Be it known that I, LOUIS WILHELM, a citizen of the United States, residing at Worcester, in the county of Worcester and State of Massachusetts, have invented certain new and useful Improvements in Lens-Blanks, of which the following is a specification.

My invention relates to blanks for bi-focal lenses, which blanks are used by opticians as the base to which is fused a small auxiliary blank or segment having a different refractive index from that of the blank proper to which it is welded to complete the lens.

Heretofore the blanks made for use in the construction of bi-focal lenses have been formed with smooth faces, whether of concave, convex, or other form, having a seat or concavity ground in some portion of the smooth face, adapted to receive fusible material for the auxiliary focal member. It is essential to the fusing process that air or gas bubbles should not occur intermediate the auxiliary material and the blank. To avoid this the block to be fused must have incomplete surface contact at the inception of the fusing process. The present method of effecting this end is to manually insert a steel piece intermediate the blank and the fusible block, but this has been unsatisfactory for several reasons; for instance, the auxiliary piece slips from between the two members or deranges their relative positions because of the smooth inclined surface upon which the steel piece rests; furthermore, the presence of the steel piece which is embedded in the parts after the fusing operation, sometimes occasions fracture of the lens parts in being ground therefrom.

The purpose of my invention is to construct a lens blank which shall overcome the above enumerated defects; and consists essentially in providing an immovable homogeneous supporting means upon the blank, and adjacent the seat of the auxiliary focal member.

In the drawings which form a part of this specification, Figure 1 is a plan view 50 of my novel blank. Fig. 2, a section of the

same on line α α of Fig. 1, showing in section an auxiliary blank positioned preparatory to fusing. Figs. 3 and 4 are similar sections respectively of the same parts during the subsequent steps of manufacture of 55 a bi-focal lens. Figs. 5 and 6, plan views of modified forms of my blank, and Fig. 7, a section on line y y of Fig. 6 showing in broken outline the auxiliary fusible member.

Like reference characters indicate like 60 parts throughout the views.

My novel blank comprises a lens body, A, which in general outline may be of any usual contour, such as concave, convex, plano-concave, or plano-convex. In this instance, the 65 body is plano-convex in form; a , indicating the convex surface. The body is formed by molding. The molds are provided with cavities and a convex projection, with the result that there is produced upon the convex 70 surface, a , of the body one or more projections, B, and a concave cavity, C. The projections are circumferentially disposed with relation to each other, and the cavity is with- 75 in and concentric with the projections. The projections are adjacent and equidistant from the margin of the cavity, C. The surface of the cavity, C, may be later ground. The projections in this instance are vertical 80 and rounded, but this particular shape is not 85 essential. In Figs. 6 and 7, the inner sides of the projections, B', are cut away to form shoulders or seats, b. In Fig. 5, the projections, B'', are arcuate in form.

In Figs. 2, 3 and 4 are shown the manner 85 in which my novel lens blank may be utilized by opticians. The operator places a disk, D, of easily fusible glass, having a different refractive index from that of the blank, A, upon the projection or projections, B. Under 90 heat, the disk sinks into the cavity, C, as shown in Fig. 3, and is fused and welded with the blank. After cooling, the projecting parts of the disk and projections are ground off and the whole polished. 95

What I claim is,

1. In a lens blank, the combination with the body, of integral projections upon the face of the body.
2. In a lens blank, the combination with 100

the body of circularly disposed integral projections upon the face of the body.

3. In a lens blank, the combination with the body provided with a concave cavity, of integral projections upon the face of the body adjacent the margin of the cavity.

4. In a lens blank, the combination with the body, provided with a concave cavity, of

integral projections circularly disposed upon the face of the body around the cavity.

In testimony whereof I have affixed my signature in presence of two witnesses.

LOUIS WILHELM.
